UNITED STATES PATENT OFFICE.

CHARLES B. LAWRENCE AND EUGENE F. MARTINET, OF CLEVELAND, OHIO, ASSIGNEES TO THE P. A. GEIER COMPANY, OF CLEVELAND, OHIO, A CORPORATION OF OHIO.

DESIGN FOR A CASING FOR AIR-TREATING MECHANISM.

Application filed October 24, 1928. Serial No. 28,608. Term of patent 14 years.

To all whom it may concern:

Be it known that we, CHARLES B. LAWRENCE and EUGENE F. MARTINET, citizens of the United States of America, residing at Cleveland, in the county of Cuyahoga and State of Ohio, have invented a new, original, and ornamental Design for Casing, for Air-Treating Mechanism, of which the following is a specification, reference being had to the accompanying drawing, forming part thereof.

The figure is a view in elevation of a casing for air treating mechanism showing our new design.

We claim:

The ornamental design for a casing for air treating mechanism, as shown.

In testimony whereof we do now affix our signatures.

CHARLES B. LAWRENCE.
EUGENE F. MARTINET.
